UNITED STATES PATENT OFFICE.

HARRY B. WHITE, OF CANTON, OHIO, ASSIGNEE TO THE GILLIAM MANUFACTURING COMPANY, OF CANTON, OHIO, A CORPORATION OF OHIO.

BOW REST AND CLAMPING DEVICE.

1,247,193.

Specification of Letters Patent. Patented Nov. 20, 1917.

Application filed October 21, 1915. Serial No. 57,081.

To all whom it may concern:

Be it known that I, HARRY B. WHITE, a citizen of the United States, residing at Canton, in the county of Stark and State of 5 Ohio, have invented a new and useful Bow Rest and Clamping Device, of which the following is a specification.

This invention relates to bow rests and 10 clamping devices adapted for supporting and clamping the bows of a vehicle top in the folded position. In the ordinary forms of bow rests such as are in use at present it is necessary to provide spacing lugs, either on the bow rest or upon the bows themselves, for the purpose of spacing and separately supporting the several bows.

The object of the present invention is to 20 provide an improved bow rest and clamping device which will support the lowermost bow of the vehicle top, and separately support and clamp the uppermost bow in the proper position, the provision of spacing lugs for separately supporting and spacing the several bows being unnecessary either upon the 25 bow rest or the bows.

A further object is to provide a simple, 30 inexpensive and efficient device of the character referred to which may be easily and readily operated to clamp or unclamp the bows.

With these objects in view the invention consists in the novel construction and arrangement of parts, hereinafter described, illustrated in the accompanying drawings, 35 and particularly pointed out in the appended claims, it being understood that various changes in the form, proportions, size and minor details of construction may be made within the scope of the appended claims, 40 without departing from the spirit or sacrificing any of the advantages of the invention.

In the drawings:

Figure 1 is a perspective view of a bow 45 rest and clamping device constructed in accordance with my invention.

Fig. 2 is a side elevation of the same showing the bows clamped therein.

Fig. 3 is a similar view showing the device 50 in the open or unclamped position.

Fig. 4 is a detail perspective view of the clamping shoe.

Fig. 5 is a detail perspective view of the operating handle.

Fig. 6 is a detail perspective view of the 55 spring link.

Fig. 7 is a side elevation of a modified form of the device showing the bows clamped therein.

Fig. 8 is an edge elevation of the same, 60 the handle being broken for purpose of illustration.

Similar numerals of reference indicate corresponding parts throughout the several figures of the drawings.

Referring more especially to the construction illustrated in the accompanying drawings, the numeral 1 indicates the supporting rod which is preferably T-shaped in cross section and is provided with a socket 70 2 by means of which said supporting rod is connected to and depends from the ordinary bracket which is provided upon automobiles and other vehicles for the purpose of receiving said rod. The upper extremity of the 75 supporting rod is of channel form as indicated by the numeral 3, the inner wall thereof being reinforced at its upper extremity as shown at 4 for the purpose of pivotally connecting the clamping shoe thereto as will 80 be hereinafter described.

The lower extremity of the supporting rod is curved as shown at 5 and provided with a pair of ears 6 by means of which the pivoted arm is connected thereto as will be 85 further described. A curved transverse rib 7 is formed integral with the supporting rod and is connected to each of the wings 6 for the purpose of strengthening the structure.

The clamping shoe 8 comprises the curved 90 portion 9, the free extremity of which is preferably curved outwardly at 10, a pair of ears 11 being formed upon the upper extremity of said clamping shoe and pivotally connected to the reinforced portion 4 of the 95 supporting rod by means of a pin 12. A shoulder 13 is formed upon the under face of each of the ears 11 and arranged to contact with the inner face of the supporting rod and a flat portion 14 is formed upon 100 the upper edge of each of said ears and adapted to contact with the shoulder 15 formed at the upper extremity of said supporting rod. A curved rib 16 is formed upon the convex face of the clamping shoe 105 and a pad 17 of leather or similar material is attached to the concaved face thereof.

The operating handle 18 is provided at

its upper extremity with an angularly disposed arm 19, which is adapted to be located between the ears 11 of the clamping shoe, a pin 20 being passed through the apertures 21 in said ears and the aperture 22 in said arm for the purpose of pivotally mounting said handle upon said clamping shoe. A barrel 23 is formed near the upper extremity of the operating lever, said barrel being provided with a slot 24 adapted to receive the straight portion 25 of the spring link 26, said link being slightly curved, the lower free extremities thereof being up-turned as shown at 27 and located in the apertures 28 formed in the channel portion 3 of the supporting rod. When the link is placed in position as described the upper edges of the slot may be squeezed together as indicated at 29.

20 The retaining arm 30 is preferably T-shaped in cross section and the lower extremity thereof is curved at 31 and provided at its lower extremity and upon each side of the web portion with a boss 32 adapted to be seated between the ears 6 formed upon the supporting arm, a pin 33 being passed through suitable apertures in said ears and retaining arm for the purpose of pivotally connecting said members together.

25 The inner lower face of the retaining arm is curved as shown at 34 in order to accommodate the lowermost bow and a pad 35 of leather or similar material is attached thereto in the usual manner.

30 The upper extremity of the retaining arm is curved inwardly in order to fit the convex face of the clamping shoe and is provided with a groove 36 adapted to receive the rib 16 formed upon said clamping shoe. The web portion of the retaining arm is tapered as indicated at 37 and adapted to be seated within the shallow groove 38 formed in the operating handle when the parts are in the closed position as shown in Figs. 1 and 2.

35 A tapered stud 39 is formed near the upper extremity of the arm and adapted to be seated within a conical aperture 40 provided in the handle, when the parts are in the clamped position as best shown in Fig. 2.

40 When it is desired to clamp the bows of a vehicle top in the bow rest above described the device is set in the opened position as shown in Fig. 3 of the drawings. The bows are then lowered between the supporting bar 1 and the retaining arm 30, the lowermost bow resting within the concaved lower portion of the retaining arm. The handle is then operated to bring the clamping shoe into engagement with the uppermost bow after which the retaining arm is swung into place against the clamping shoe, the groove 36 therein receiving the rib 16 of the clamping shoe. The handle is then moved down into the clamping position, 45 clamping the shoe against the uppermost

bow and as the link 26 passes over the center the handle will be held tightly in position, the shallow groove 38 therein receiving the curved portion 37 of the web located upon the retaining arm. As the link is formed of spring material it will thus hold the handle firmly in the clamped position. It will be noted that as the clamping shoe is operated by means of the handle, said shoe automatically forces the uppermost bow 75 downwardly into position and clamps said bow against side movement. The tapered stud 39 is received in the conical aperture 40, in the handle, as said handle is moved into the clamped position, and thus binds 80 the retaining arm and handle together while in the clamped position, preventing any side movement of either of said members, while the several ribs and grooves formed upon the several members hold the shoe, retaining 85 arm and handle in alinement. The concaved portion 34 of the retaining arm engages the lowermost bow of the vehicle top and holds said bow against upward or outward movement. The uppermost and lowermost bows of the vehicle top are thus separately supported and clamped in position, the intervening bows assuming the proper positions between said upper and lower bows and with this construction no spacing lugs 90 upon the bows themselves or supporting or spacing members upon the bow rest and clamping device are necessary. The retaining arm will furthermore prevent any accidental horizontal displacement of the intervening bows.

In Figs. 7 and 8 is illustrated a modified form of the device. Referring more especially to the construction illustrated in these figures the numeral 1'' indicates the supporting rod which is preferably T-shaped in cross section and is provided with a socket 2'' by means of which the supporting rod is connected to and depends from the ordinary bracket which is provided upon automobiles 105 and other vehicles for the purpose of receiving said rod. The upper extremity of the supporting rod is of channel form as indicated by the numeral 3'', the inner wall thereof being reinforced at its upper extremity for the purpose of pivotally connecting the clamping shoe thereto as will be hereinafter described.

The lower extremity of the supporting rod is curved as shown at 5'' and provided with 120 a pair of ears 6'' by means of which the pivoted retaining arm is connected thereto. The clamping shoe 8'' comprises the curved portion 9'', a pair of ears 11'' being formed upon the upper extremity of said clamping 125 shoe and pivotally connected to the reinforced portion of the supporting rod by means of a pin 12''. The shoulder 13'' is formed upon the under face of each of the ears for the purpose of engaging the inner 130

face of the supporting rod when the shoe is in the lowered or clamped position and a flat portion 14" is formed upon the upper edge of each of said ears and adapted to 5 contact with the shoulder 15" formed at the upper extremity of the supporting rod. A curved rib 16" is formed upon the convex face of the clamping shoe and a pad of leather or similar material 17" is attached 10 to the concaved face thereof.

15 The operating handle 18" is provided at its upper extremity with the angularly disposed arm 19" which is adapted to be located between the ears 11" of the clamping shoe, a pin 20" being provided for the purpose of pivotally connecting said handle to the clamping shoe. The spring link 26" connects the operating handle with the channel portion of the supporting rod.

20 The retaining arm 30" is preferably T-shaped in cross section and the lower extremity thereof is curved at 31" and pivotally connected to the curved portion of the supporting arm by means of a pin 33", the 25 inner lower face of the retaining arm is concaved as shown at 34" in order to accommodate the lowermost bow and a pad 35" of leather or similar material is attached thereto in the usual manner.

30 The upper extremity of the retaining arm is provided with a socket 45 adapted to accommodate the tongue 46 provided upon the lower extremity of the clamping shoe when the parts are in the clamped position. The 35 curved rib 16" and the upper portion of the web 37" of the retaining arm are adapted to be seated within the shallow groove 38" formed in the operating handle, when the parts are in the clamped position.

40 When it is desired to clamp the bows of a vehicle top in this modified form of bow rest the device is set in the open position and the bows are then lowered between the supporting arm 1" and the retaining arm 45 30", the lowermost bow resting within the concaved lower portion of the retaining arm. The retaining arm is then swung into position and the handle is operated to bring the clamping shoe into engagement with the

50 uppermost bow and as the handle is moved down into the clamping position, clamping the shoe against the uppermost bow, the link 26" passes over the center, thus holding the several parts tightly clamped into position, 55 the tongue 46 of the clamping shoe resting within the socket 45 of the retaining arm, while the rib of the clamping shoe and the web of the retaining arm are located within the shallow groove formed in the operating 60 handle, thus retaining the arm, shoe and handle in alignment.

As is well understood by those versed in the construction of vehicle tops such as are commonly used upon automobiles and the 65 like each top consists of a plurality of bows

hingedly connected at their lower extremities upon each side of the vehicle body, each bow being connected at its upper extremity to the corresponding bow upon the opposite side of the vehicle by means of a bar or rod 70 extending across the top. Thus the natural tendency of each bow is to spring outwardly away from the vehicle body as the bows, as well as their connecting rods, are formed of spring material or of material of a slightly 75 springy nature. When the bows of the top are folded down into the closed position the top bow of the set must be forced down considerably in order to be clamped within the bow rest and clamping device. With the 80 ordinary forms of bow rests and clamping devices it is necessary to force this upper bow down with one hand while the clamping device is operated with the other hand to hold the bows in the folded position. With 85 the present bow rest and clamping device embodying the invention disclosed in this application it is not necessary for the operator to draw the bows down by hand; the bows are merely lowered until the lower 90 bow rests upon the rest member 5, after which the retaining arm is moved into position and the operating lever moved downwardly bringing the clamping shoe downwardly, contacting with the upper bow of 95 the set and forcing said upper bow downwardly as well as inwardly and when the operating lever is moved to the limit of its downward movement the retaining arm and clamping shoe are thus locked in the closed 100 position, clamping the bows in the folded position, the upper bow due to the springy nature of the bows and the construction thereof above pointed out being forced outwardly against the clamping shoe and resting upon the projection 17 thereof, the intermediate bows being properly spaced between the upper and lower bows, while the lower bow is held in position by means of the projection 35 upon the retaining arm. 105 The entire set of bows is thus quickly and easily forced into the clamped position and held in the clamped position by the action above described.

Although the drawings and above specification disclose the best mode in which I have contemplated embodying my invention I desire to be not limited to the details of such disclosure, for, in the further practical application of my invention, many 115 changes in form and construction may be made, as circumstances require or experience suggests, without departing from the spirit of the invention, within the scope of the appended claims.

120 I claim:

1. A device of the character described comprising a supporting rod, a curved clamping shoe pivotally mounted upon the upper extremity of the supporting rod and 130

arranged to separately support and clamp the uppermost bow of a vehicle top, a retaining arm pivotally mounted upon the lower extremity of said supporting rod and 5 arranged to be held in position by said clamping shoe and means for holding said clamping shoe in the clamped position.

2. A device of the character described comprising a supporting rod, a curved 10 clamping shoe pivotally mounted upon the upper extremity of the supporting rod and arranged to separately support and clamp the uppermost bow of a vehicle top, a retaining arm pivotally mounted upon the lower 15 extremity of said supporting rod, the upper extremity of said retaining arm being adapted to be engaged by the lower extremity of said clamping shoe when the parts are in the clamped position, and means for holding 20 said clamping shoe in the clamped position.

3. A device of the character described, comprising a supporting rod, a curved 25 clamping shoe pivotally mounted upon the upper extremity of the supporting rod and arranged to separately support and clamp the uppermost bow of a vehicle top, a retaining arm pivotally mounted upon the lower extremity of said supporting rod and provided with a socket in its upper portion, a 30 tongue formed upon said clamping shoe and arranged to be seated within said socket when the parts are in the clamped position and means for holding 35 said clamping shoe in the clamped position.

4. A device of the character described, comprising a supporting rod, a clamping shoe pivotally mounted upon the upper extremity of said supporting rod, and arranged to separately support and clamp the uppermost bow of a set of top bows, a retaining arm pivotally connected to the lower extremity of said supporting rod and arranged to be clamped in position by said 45 clamping shoe and means for holding said clamping shoe in the clamped position.

5. A device of the character described,

comprising a supporting rod, a curved clamping shoe pivotally mounted upon the upper extremity of said supporting rod and 50 arranged to separately support and clamp the uppermost bow of a set of top bows, an operating handle pivotally mounted upon said clamping shoe, a retaining arm pivotally mounted upon the lower extremity of 55 said supporting rod and adapted to separately support and clamp the lowermost bow of the set, the upper extremity of said retaining arm being arranged to be engaged by said clamping shoe and means for holding 60 all of said members in the clamped position.

6. A device of the character described, comprising a supporting rod, a curved 65 clamping shoe pivotally mounted upon the upper extremity of said supporting rod and arranged to separately support and clamp the uppermost bow of a set of top bows, a tongue provided upon said clamping shoe, an operating handle pivotally mounted upon said 70 clamping shoe, a retaining arm pivotally mounted upon the lower extremity of said supporting rod and adapted to separately support and clamp the lowermost bow of the set, the upper extremity of said retaining 75 arm being provided with a socket arranged to receive said tongue when the parts are in the clamped position and means for holding 80 all of said members in the clamped position.

7. A device of the character described, comprising a supporting rod, a clamping shoe pivotally mounted upon the upper extremity of said supporting rod and arranged to separately support and clamp the uppermost bow of a vehicle top, a retaining arm pivotally mounted upon the lower extremity of said supporting rod and arranged to engage 85 said clamping shoe and means for holding said clamping shoe and retaining arm in the clamped position.

In testimony that I claim the above, I have hereunto subscribed my name.

HARRY B. WHITE.
